UNITED STATES PATENT OFFICE

170,761

AUTOMOBILE STONE SHIELD

Melvin C. Mawhinney, Detroit, Mich., assignor to Chrysler Corporation, Highland Park, Mich., a corporation of Delaware

Application May 12, 1953, Serial No. 24,973

Term of patent 7 years

(Cl. D14—6)

To all whom it may concern:

Be it known that I, Melvin C. Mawhinney, a citizen of the United States, residing in the city of Detroit, county of Wayne, and State of Michigan, have invented a new, original, and ornamental Design for an Automobile Stone Shield, of which the following is a specification, reference being had to the accompanying drawings, forming part thereof, in which:

Fig. 1 is a side elevational view of an automobile stone shield showing my new design; and

Figs. 2, 3, 4 and 5 are sectional views taken on the lines 2—2, 3—3, 4—4 and 5—5 respectively of Fig. 1.

I claim:

The ornamental design for an automobile stone shield, substantially as shown.

MELVIN C. MAWHINNEY.
